UNITED STATES PATENT OFFICE.

ALBERT B. CAWTHRA, OF WORCESTER, MASSACHUSETTS.

SURGICAL SUPPORT

Application filed September 11, 1922. Serial No. 587,372.

To all whom it may concern:

Be it known that I, ALBERT B. CAWTHRA, a citizen of the United States, residing at Worcester, in the county of Worcester and 5 State of Massachusetts, have invented a new and useful Surgical Support, of which the following is a specification.

The object of this invention is to provide a new and improved medical support. In 10 many diseases and after certain surgical operations it is necessary to support the male organs on account of the swelling or weak condition. This is usually done by attaching the ends of strips of surgical plaster to 15 the thighs and by building up a platform in this way. This is not very satisfactory because it is not hygienic and because the support has to be renewed very often, it being very painful to the patient to remove 20 the strips of plaster.

I have provided a support which can be used for this purpose. My improved support consists of a sheet or board, preferably made of antiseptic material. A narrow- 25 mouthed notch is cut in one side of this board, this notch having its inner edge grooved and having the sides of the narrow mouth rounded. A support of this character can be placed under the organs, and by 30 the shaping of the notch it will be held in position and the organs will be comfortably supported thereon. The support can be easily placed in position or removed, and can be easily cleaned by boiling or by washing 35 in an antiseptic solution. The device has proved efficient in practice and has relieved a great deal of suffering.

The preferred form of the device is illustrated in the accompanying drawing, in 40 which

Fig. 1 shows the human figure in outline with the device in position;

Fig. 2 is a perspective view of the device.

In detail, in the drawing A designates a 45 sheet or board which has a notch B cut or

formed in one side thereof, the inner edge of the notch being rounded as at C, and the notch having a narrow mouth D, the sides of the narrow mouth being curved all around it as at E. In practice the device has 50 been made out of hard and smooth fiber, but any material suitable for the purpose may be employed. The details and shape of the device may be varied without departing from the scope of my invention as expressed 55 in the claims.

Having thus fully described my invention what I claim and desire to secure by Letters Patent is:

1. A support of the character described 60 for sustaining the genital organs of a male human being, consisting of a board having a notch in one side thereof to accommodate said organs.

2. A support of the character described 65 for sustaining the genital organs of a male human being, consisting of a board of antiseptic material having a notch in one side thereof to accommodate said organs.

3. A support of the character described 70 for sustaining the genital organs of a male human being, consisting of a board having a narrow-mouthed notch in one side thereof to accommodate said organs.

4. A support of the character described 75 for sustaining the genital organs of a male human being, consisting of a board having a notch in one side thereof, the inner edge of the notch being curved, to accommodate said organs.

5. A support of the character described 80 for sustaining the genital organs of a male human being, consisting of a board having a narrow mouthed notch in one side thereof, the inner edge of the notch being curved 85 and the sides of the mouth being rounded, to accommodate said organs.

In testimony whereof I have hereunto affixed my signature:

ALBERT B. CAWTHRA.
